UNITED STATES PATENT OFFICE.

JOHN M. VAN ORDEN, OF NEWARK, NEW JERSEY.

DESIGN FOR A CORSET.

SPECIFICATION forming part of Design No. 34,808, dated July 16, 1901.

Application filed April 22, 1901. Serial No. 57,022. Term of patent 14 years.

To all whom it may concern:

Be it known that I, JOHN M. VAN ORDEN, a citizen of the United States, and a resident of Newark, Essex county, New Jersey, have invented and produced a new and original Design for Corsets, of which the following is a specification.

In the drawings, Figure 1 is a view in perspective of a corset embodying my novel design, while Fig. 2 is a view thereof in side elevation.

The novel and pleasing effect constituting my invention resides in the ensemble of the corset, is fully illustrated in the drawings and capable of being understood clearly and readily upon inspection thereof, and for the sake of convenience in reviewing the drawings I have attached letters of reference to some of the salient points.

The reference-letter *a* designates the

straight fore part of the corset, from which at the bottom extend toward the rear on both sides belt-like members *b*, while at the top the superior edges *c* part in an angle opening upwardly, and between this region and their juncture in the rear exhibit a rather flat convexity, the general plane of the upper boundary of the corset being tilted forward.

Having thus described my design, what I claim, and desire to secure by Letters Patent, is—

The design for a corset substantially as herein shown and described.

In testimony whereof I have signed my name to this specification in the presence of two subscribing witnesses.

JOHN M. VAN ORDEN.

Witnesses:

ALEXANDER C. PROUDFIT,

JOHN FLYNN.
